UNITED STATES PATENT OFFICE.

JACOB FELBEL, OF NEW YORK, N. Y., ASSIGNOR TO REMINGTON TYPEWRITER COMPANY, OF ILION, NEW YORK, A CORPORATION OF NEW YORK.

TYPE-WRITING MACHINES.

1,185,299.

Specification of Letters Patent.

Patented May 30, 1916.

Application filed October 30, 1915. Serial No. 58,821.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

- 10 My present invention relates primarily to the universal bar mechanism of type-writing machines and its main object is to provide new and improved mechanism of the character specified.
- 15 More particularly my invention has to do with a type bar operated universal bar which is shiftable automatically during the case shifting operation but is mounted independently of the element which is shiftable to 20 effect the change of case, this element in the present instance being the type bar segment or support. This independent mounting of the universal bar enables it to be disconnected at will so that it will not participate 25 in the case shifting movement or so that it may itself be separately shifted; constructions which may be taken advantage of for various purposes, for instance, enabling a 30 simple and effective dead key or accent key construction to be provided. In carrying out my invention novel case shifting mechanism is provided.

To the above and other ends my present invention consists in the features of construction, combinations of devices and arrangements of parts hereinafter described and particularly pointed out in the claims.

In the accompanying drawings which illustrate several adaptations of my invention, Figure 1 is a front to rear vertical sectional view taken about centrally of a typewriting machine showing one form of my invention applied thereto, some of the parts of the machine being omitted. Fig. 2 is a vertical transverse sectional view taken on a plane indicated by the dotted line $\nu-\nu$ in Fig. 1 and looking rearward. Fig. 3 is a detached perspective view of the universal bar and the shiftable frame that supports it. Figs. 4 and 5 are fragmentary front elevations showing modifications in the way of mounting the shiftable frame or support for the universal bar on a stationary part

of the machine, in the present instance, the guide posts for the type bar segment. Figs. 55 6 and 7 are respectively fragmentary face and plan views of a further modification of the mounting of the shiftable frame. Fig. 8 is a fragmentary vertical sectional view taken from front to rear and illustrating a 60 modification of my invention. Fig. 9 is a view corresponding to Fig. 8 but showing the parts after the shift key has been operated. Fig. 10 is a view corresponding to Fig. 8 but showing the parts as they appear 65 after the actuation of both the shift key and of a special or accent printing key. Figs. 11, 12 and 13 are diagrammatic views illustrating the relationship of the type segment and universal bar in positions corresponding respectively to Figs. 8, 9 and 10. Fig. 14 is a fragmentary front elevation partly in section of a further modification 70 of my invention. Fig. 15 is a fragmentary plan view of the construction shown in Fig. 75 14. Fig. 16 is a fragmentary perspective view showing parts of the construction illustrated in Figs. 14 and 15. Fig. 17 is a fragmentary perspective view showing a 80 modification of the construction illustrated 85 in Fig. 14.

Referring first to the construction illustrated in Figs. 1 to 3, inclusive, the machine shown, though differing in details, generally resembles the Monarch typewriter, 85 and has a main frame comprising a base 1, posts 2 and a top plate 3 above which are fixed track-ways 4 that coöperate through anti-friction balls 5 with the rear or slide bar 6 of a carriage which further comprises 90 forwardly extending end bars 7 that provide bearings for a rotary platen 8. Carried by the carriage is a pivotally mounted feed rack 9 that is normally maintained in spring-pressed engagement with a feed pinion 10 that is operatively connected 95 through a shaft (not shown) with a toothed escapement wheel 11, said shaft being supported in a bearing in the tubular stationary bracket 12, as in the Monarch machine. Co-operative with the escapement wheel 11 are escapement dogs 13 and 14 mounted at the top of a carrier 15 that is pivotally supported on a bracket 16 that depends from the top plate. A spring 17 normally maintains a stop 18 mounted on the carrier 15

in contact with the bracket 16, in which position the rear dog 13 is engaged with the escapement wheel 11. The dogs 13 and 14 are or may be of the usual Monarch construction but are in the reverse of the ordinary arrangement; that is, the rear dog 13 may be the stepping or loose dog and the forward dog 14 the fixed dog. The carrier 15 is rocked or swung toward the rear and then forward again to produce step-by-step feed movements of the carriage under the pull of the usual carriage motor or spring drum (not shown). The means for rocking the carrier 15 are of novel construction to be hereinafter described.

Coöperative with the front face of the platen 8 are a segmentally arranged series of type bars 19, each type bar having fixed to its free end a block provided with two types, the outer type 20 being the lower case type and the inner type 21 being the upper case type. The type bars may be pivoted on a common pivot wire 22 which is mounted on a shiftable type bar segment or element 23, in any well-known or desirable manner. The type bars fit in and are partly guided by converging slots in the segment. Each type bar is connected by a link 24 with an upright sub-lever 25 which is pivoted on a key lever 26, said sub-lever being slotted at 27 near its lower end to cooperate with a fixed abutment 28. The set of key levers 26 fulcrum on a plate 29 mounted in the rear portion of the base and each key lever is provided with a key or button 30 and with a restoring spring 30a. Near their outer end portions the type bars are normally supported by a curved rest 31 which is mounted on a frame 32 secured to bars or rods 33 that are rigid with and project forward from the segment or type bar support 23. Said segment and said rest are shiftable at will to change case by key operated case shifting devices of suitable construction. At its opposite ends or sides the segment is provided with grooved track portions which coöperate through anti-friction balls with oppositely grooved trackways that are mounted on stationary posts 34 rising from the base 1. The sets of balls at the sides of the segment are controlled by separators 35. For limiting up and down movements of the segment along the stationary supports or posts, stop devices 36 are provided comprising at each end of the segment an upper stop 36 and a lower stop 37 both on the segment itself. Coöperating stop devices 38 and 39 are adjustably secured in pairs to the rear faces of the posts 34. The ball bearing mounting of the segment and the stop devices therefor may be of the usual Monarch construction.

To support the segment 23 and shift it up and down, devices are provided which are connected to lugs or ears 40 extending

downward from the segment, one near each end thereof. Said devices comprise a pair of upright links or bars 41, the upper ends of which are pivotally connected at 42 to the outer faces of the lugs 40. The lower ends of said links are perforated to pivotally engage headed pins or shoulder screws 43 that are secured to the rear free ends of crank arms 44, said pins extending laterally outward from said crank arms. Said crank arms have hubs 45 that fit over a key controlled element or rock shaft 46 and are fixed to said rock shaft near its ends by set screws 47. The rock shaft is mounted on pointed pivot screws 48 that are threaded into the sides of the base 1. Between the hub 45 of each crank arm and the adjacent end of the rock shaft there is fitted over said rock shaft a hub 49 of a forwardly extending crank arm 50, said hub being pinned or otherwise fixed to said rock shaft, so that both crank arms 50 are rigid therewith. Fitting loosely over the rock shaft 46 inside each crank arm 50 and extending forward contiguous to said crank arm is a thin arm 51 which is secured to the crank arm by a screw 52. Said arm 51 is longer than the crank arm and provides a bearing at its outer end for a roller 53 that underlies a shift key lever 54, there being two of these shift key levers one at each side of the machine. Each shift key lever is pivoted on a pin or pivot screw 55 near its rear end, said pin being supported on a stationary bracket 56. Each shift lever 54 is provided with a shift key 57 and behind its pivot or fulcrum 55 is located a restoring spring 58 which tends to return it after actuation. A depression of either shift key operates on the underlying roll 53 to swing down the arms 51 and 50, rocking the shaft 46 and swinging the crank arms 44 upward, this upward movement of the crank arms 44 being transmitted through the links 41 to the type bar support comprising the segment 23 which is thereby shifted or raised to an extent limited by the engagement of the stops 37 with their associate stops 39. The result of this shifting movement is to render the upper case types 21 operative when the type bars are actuated, the types 20 having been carried upward so that they will not strike against the platen. When the shift key is released the type bar segment and connected parts are restored by gravity to normal position where the stops 36 engage with their associate stops 38. Counterbalancing springs 59 are provided which tend constantly to lift the type bar support and in a measure overcome the weight of said support, although not having tension enough to lift the support from its normal position in which the stops 36 engage with the stops 38. The effect of these springs, however, is to render the touch on the shift

keys much lighter. The springs 59 are connected at their forward ends to pins 60 fixed to and extending downward from the rock shaft 46 while the rear ends of said springs are anchored to adjustable hooks 61 that are threaded into the inner end portions of the pivot pins 55. Preferably there may be provided shift locking devices of suitable construction such as that found in the Monarch machine and which will shift and maintain the type bar segment and other shifted parts in shifted position on the operation of a locking key-lever indicated at 62, the parts being locked by the actuation of the associate shift key 57 at the left-hand side of the machine.

The universal bar according to my present invention is mounted to reciprocate on a frame or support which in turn is movably mounted on the frame of the machine or a stationary part thereof so that said universal bar support is entirely separate from and independent of the case shifting element or type bar support 23, although said universal bar support may shift concurrently with the type bar support and in the present instance is adapted to be shifted automatically upon actuation of either one of the shift keys 57 and the shift key lever 62. Thus the universal bar itself, instead of being mounted on the case shifting element as in prior constructions, is mounted independently thereof, being supported from the frame of the machine by an intermediate shiftable frame or part. Said frame in the present instance as best illustrated in Fig. 3 comprises an upright segmental plate 63 which is adapted to fit into the curved opening above the type bar pivots. Said plate is provided with straight, lateral extensions 64 which terminate in forwardly curved lugs 65 in which are fixed downwardly extending pins or bearing devices 66. Fixed to and extending rearward from the plate near its middle is a bearing rod 67 terminating in a detachable head 68 while near the ends small bearing pins or devices 69 are fixed to and extend rearward from said plate. The rod 67 and pins 69 provide bearings for a slidably mounted universal bar frame designated as a whole by the reference numeral 70 and comprising a cross bar or portion 71 provided with a central depression 72 to afford play of the ribbon vibrator (not shown). Fixed to and extending rearward and inward from the cross portion are angular branches 73 and 74 which unite in a single, rearwardly extending stem 75 provided with a bearing block 76 that fits over and slides on the rod 67. Upright ears 77 at the ends of the cross bar 71 are perforated to fit over the guide pins 69. The end portions of the cross bar are also provided with upwardly extending ears 71^a to which are fixed the universal bar proper 78, said uni-

versal bar being arcuate in shape and being close to the under edge of the supporting plate or frame 63, said universal bar being provided with an upturned edge or lip which is adapted to be actuated directly by the type bars as presently to be described. The bar 78 is normally maintained forward with the ears 77 in contact with the rear face of the plate 63 by a coiled spring 79 which is connected at its rear end to the universal bar frame and at its front is anchored to the plate. Movements of the universal bar when actuated are limited by the head 68. The universal bar proper and the universal bar frame 70 together with the means of slidably supporting the same are substantially the same as is disclosed in the application of Bond & Joselyn, Sr. No. 18,987, filed April 3, 1915. As has been stated the mounting of the support or frame 63 is novel and is different from that found in said Bond & Joselyn application.

In order to support and guide the frame 63 and the universal bar carried by it, a pair of supporting brackets 80 are employed, one secured to each of the posts 34 at its front upper side by screws 81. Each bracket is provided with an ear 82 perforated to receive one of the guide pins 66, the construction permitting a slidable up and down movement of the frame 63 and the universal bar parallel with movements of the type bar segment. When mounted in place the frame 63 is in the curve of the type bar segment, the lateral portions 64 extending over the ends of said segment while the universal bar is arranged between the top of the type bar segment and the curved bottom of the frame 63 and in such position that its upturned edge is above the type bar pivots when in position to be actuated by actuating faces 19^a with which the type bars are provided. The universal bar frame is connected with the dog carrier 15 in order to transmit movement from the type bar to said dog carrier by a link or rod 83 which has a loose or pin-and-slot connection at its rear with the dog carrier, said rod 83 being provided with a slot 84 which receives a screw 85 that is threaded into the right-hand side face of said carrier. At its forward end the rod 83 is pivotally connected with the universal bar frame 70 by a pivot screw 86. It will be understood that when one of the type bars is operated its face 19^a will toward the end of the stroke strike the universal bar proper 78 and slide the universal bar frame rearward, over-coming the spring 79, this movement being independent of the supporting frame 63 and being transmitted through the rod or connector 83 to the carrier 15, causing the latter to swing rearwardly, disengaging the dog 13 from the escapement wheel 11 and bringing the dog 14 into engagement therewith. When the

printing key is released the parts will be restored to normal position by the restoring springs, the dog 14 moving out of the escapement wheel and the dog 13 reengaging therewith at the next succeeding tooth. As a result of this reciprocation of the escapement devices the carriage will advance a letter space distance toward the left.

The means for automatically shifting the universal bar when the case shifting mechanism comprising the key controlled shiftable element or segment 23 is operated, comprise connections between the support or frame 63 and the rock shaft 46. Said connections include a pair of upright arms or links 87 arranged just outside the shift links 41. Each arm 87 is provided at its upper end portion with an inturned lip or ear 88 which receives a headed screw 89 that is threaded into the lateral extensions 64, the arm however being preferably loosely supported by said screw. At its lower end the arm 87 is perforated to fit over the associate screw or stud 43 outside the link 41. The construction is such that when the actuation of either of the keys 57 or of the key 62, causes the rocking of the shaft 46 and the upward swinging of the crank arms 44 and the shifting of the type bar segment, the arms 87 will be concurrently moved upward, shifting the frame 63 which carries with it the universal bar, so that the universal bar shifts automatically with the type bar segment. Said universal bar of course will be restored to lower case position when the type bar segment returns. It will be understood that the type bar support and the universal bar support may be shifted downwardly to upper case position if desired instead of upwardly as shown here.

Various modifications of the construction last described may be resorted to, some examples of such modifications being illustrated in Figs. 4 to 7, inclusive, which relate to some of the changes which may be made in the mounting of the universal bar supporting frame. As shown in Fig. 4 each of the guide pins 66 may coöperate with a bracket 90 which differs from the bracket 80 in having two perforated guiding ears 91 one near the top and one near the bottom of the bracket. This is also true of the bearing illustrated in Fig. 5 in which each bearing pin 66^a is adapted to fit into an elongated perforation indicated at 92, this perforation being in a stationary part 93.

In the modification illustrated in Figs. 6 and 7, Fig. 6 is a plan and Fig. 7 an elevation of a sliding construction which may replace the guide pins of the former constructions. A guide or track-way 94 which may be T-shaped in cross section is fixed to the front of the post 34 and the end portion 64^a of the universal bar support is provided with a T-shaped slot or opening by which the

support is fitted over the track-way 94 and is adapted to slide up and down thereon.

No ribbon mechanism is illustrated in the drawing but the construction illustrated in Figs. 1 and 2 as well as the constructions 70 presently to be described may be equipped with the usual ribbon feeding mechanism of the Monarch machine or any other suitable ribbon mechanism; together with ribbon vibrating mechanism which may be connected to be operated from the type bar actuated universal bar, although if preferred the vibrator may be actuated in the usual way by a universal bar actuated from the key levers. The segmental supporting plate 63, 80 as best appears from Fig. 3, and the corresponding part, plate or frame in the other constructions are provided each with a central vertical slot to accommodate some of the vibrator actuating devices. Each of the constructions may also be provided with a center guide for the type bars, this center guide being mounted on the support for the universal bar and participating in the shifting movements of said support. 90

A construction embodying an extension or further modification of my invention is illustrated in Figs. 8-13, inclusive. In said construction provision is made for shifting the universal bar automatically from lower 95 to upper case position when a case-shifting key is actuated, and furthermore a special printing key is provided which is effective automatically to restore the universal bar from upper to lower case position concurrently with the operation of the connected type bar which is so constructed that it is ineffective to actuate the universal bar at this time. The consequence is that though the type bar will print the carriage will 100 not space, making a construction which is simple and effective for use with an accent type, or, as it is sometimes called, a dead key mechanism. Referring more specifically to Figs. 8 to 13 a platen 95 which is diagrammatically illustrated is adapted to be struck at its front face by type bars 96 arranged in a segmental series, each type bar being provided with two types. The central type bar, which alone is illustrated, 110 has a lower case type 97 which may be any desired character while the upper case type 98 may be an accent mark or the like. All of the type bars are provided with actuating faces or edges for coöperation with a universal bar but the actuating face 99 of the illustrated or accent type bar is partly cut away toward the pivot of the bar providing a slot or depression indicated at 100. As in the first described construction the type 115 bars may be pivoted on a common wire 101 which is mounted on a shiftable element or type bar supporting segment 102, the type bars fitting in converging guiding slots in said segment. Suitable devices are provided 120

130

for actuating the type bars to cause them to print, such for example, as trains of key operated devices like the one shown in Fig. 11 of my Patent No. 657,927, granted Sept. 18, 1900. This train comprises for each type bar a horizontally disposed link 103 which at its rear end is connected to the type bar below the pivot and at its forward end is connected to the upper end of a bent lever 104, which lever as in my said patent is pivotally attached to a downwardly extending ear 105 on a key lever 106, said lever 104 also engaging loosely with a stationary cross rod or abutment (not shown). The set of key levers 106 is fulcrumed at the rear on a stationary pivot rod 107 which is supported at its ends on the base frame 108 of the machine. Rising from the base at opposite sides are posts or stationary supports 109 on which the segment 102 is suitably guided and supported, as for example in the Figs. 1-3 construction. Near their outer ends the type bars are normally sustained by a rest 110 which in turn is supported from the segment and shifts up and down therewith.

The segment shifting devices may correspond with those of the Figs. 1-3 construction and will be briefly described. Lugs 111 at the sides of the segment have pivotally connected to them at 112 the upper ends of links or arms 113 which at their lower ends pivotally engage with lateral headed pins or studs 114 on crank arms 115 which are rigid on a rock shaft 116 which has stationary bearings supported in the base frame. Forwardly extending arms 117 which are maintained rigid with said rock shaft are provided with rollers 118 which underlie and are adapted to be actuated by shift key levers 119. Said levers have stationary pivots 120 and are provided at their rear end portions with suitable restoring springs 121 at their front ends with keys or buttons 122.

The universal bar frame 123 similar to the Figs. 1-3 construction is provided with a curved universal bar proper 124 and is slidably mounted on a rod 125 and pins 126 which project rearward from a shiftable supporting frame or plate 127. Said universal bar frame is connected as in the Figs. 1-3 construction with a dog carrier 15' by a link 83', the carrier supporting dogs 13' and 14' which coöperate with an escapement wheel 11'. The frame 127 is slidably mounted on the posts 109 independently of the segment 102 as in said Figs. 1-3 construction, but the means for shifting the universal bar and its support 127 up and down are different from the means in said construction. In the present instance the shifting means comprise two upright arms 128 having lateral ears 129 which are connected by screws 130 to the front of the plate 127, said arms at their lower ends be-

ing broadened somewhat and formed with vertical slots indicated at 131 to fit loosely over one of the lateral studs 114 outside the associate link 113. Draw springs 132 connected at their lower ends to rearwardly extending perforated ears 128' on the arms 128 and anchored at their upper ends to stationary pins 133 tend constantly to draw the arms 128 upward and lift the support 127 and the universal bar. When the parts are in lower case position as illustrated in Fig. 8 the springs 132 maintain the lower ends of the slots 131 engaged with the studs 114. The tension of the springs 132 is not sufficient, however, to overcome the weight of the segment 102 and its type bars so that the studs 114 act normally as stops to limit the upward movement of the universal bar and its supporting frame 127. The lower ends of the arms 128 are connected by a cross rod 134 which lends stiffness to the arms tending to prevent a lateral vibration or displacement. The cross rod also has the functions of a stop being adapted as presently to be described to contact with the lower end or face 135 of a device or extension 136 which is suitably fixed to or formed integrally with the special or accent key lever 106. In lower case position the face 135 is above and separated from the rod 134.

Referring to the operation of the construction just described the parts when set for writing lower case characters are in the positions illustrated in Fig. 8, at which time if the accent key lever 106 is operated, its lower case type 97 will coöperate with the platen 95 and its actuating face 99 will strike the universal bar 124, causing the frame 123 to slide rearward, said frame being connected to operate the escapement dogs. The actuation of the key lever 106 at this time is not sufficient to bring the face 135 into contact with the rod 134. The relationship between the type bar support 102 and the universal bar 124 in normal lower case position is illustrated in Fig. 11. When it is desired to print with the accent type 98 the first operation is to depress the shift key 122, causing a change in the relationship of the parts which is illustrated in Fig. 9. The effect of actuating the shift key is to rock the shaft 116, swinging upward the crank arms 115 and studs 114 and thereby through the links 113 shifting the segment 102 and the type bar supported thereon to upper case position. As the studs 114 move upward the springs 132 become effective to lift the arms 128 and shift the supporting frame 127 together with the universal bar 124. The shifting movement of the universal bar will continue until its supporting frame is arrested by the engagement of the cross rod 134 with the face 135 at which time the universal bar will be in upper case position, its relationship with the

type bar support 102 and the type bars being the same as in lower case but said support and said universal bar both being at this time raised above the normal lower case position. This will be better understood by a comparison of Fig. 12, which illustrates the two parts as they are at this time, with Fig. 11. If with the parts related as in Fig. 9 the key lever 106 controlling the accent type 98 be actuated, the face 135 acting against the rod 134 will overcome the springs 132 and move the arms 128 downward, returning the frame 127 to its lower position and restoring the universal bar automatically to lower case position while concurrently the connected type bar 96 will be operated, causing the accent type 98 to co-operate with the platen. The restoration of the universal bar, however, to lower case position has brought it opposite the notch 100 so that the type bar will not be effective to actuate the universal bar but will print without causing any escapement movement of the carriage. The relationship of the parts in printing position is illustrated in Fig. 10, while the relationship of the universal bar in respect to the type bar support 102 is diagrammatically shown in Fig. 13 where it may be readily compared with the relationships of the same parts when they are in the earlier positions.

Referring to the form of my invention above described in connection with Figs. 8 to 13, inclusive, it will be observed that there is provided a case shifting element, in the present instance, a type bar supporting segment and a shiftable universal bar, in combination with means controlled by a single key for simultaneously shifting said element and said universal bar, and other means for shifting said universal bar independently of said single key; that said single key, in the present instance, is a case shifting key; that the means for shifting the universal bar independently of the case shifting key comprises a printing key lever connected to the accent type bar; that said printing key lever shifts the universal bar to change its case position in an opposite direction from that in which it is shifted by said shift key; that means are provided tending constantly to shift the universal bar in the present instance from lower to upper case position, said means being spring means or more specifically still two springs one connected to each of two links or arms that are comprised in devices for shifting the universal bar to change its case position; that said shifting devices further comprise a shiftable frame on which the universal bar is movable by the operation of the type bars; that stop means normally prevent the operation of said spring means, said stop means in the present instance being lugs or pins extending laterally from crank arms

on a rock shaft that is controlled by the case shifting keys; and that said stop means or stops move automatically when a shift key is actuated, this automatic movement permitting the spring means to become effective. 70

Still another modification embodying some of the principles of my present invention is illustrated in Figs. 14 to 16, inclusive. In this construction the type bar system, the mounting of the segment and universal bar and the devices for shifting these elements correspond substantially with the Figs. 1-3 construction and need be but briefly described. In the Figs. 14-16 construction, however, provision is made for disconnecting the universal bar and its supporting frame so that the case-shifting keys will be ineffective on the universal bar which will remain in lower case position at all times both when the type bar segment is in lower case position and when it is shifted to upper case position. The throwing of the universal bar out of the control of the shift keys and the restoration of said universal bar to such control is preferably effected at will through the actuation of a special key. 80

Referring to Figs. 14, 15 and 16, rising from the base frame 137 are stationary posts 138 on which the type bar segment 139 is mounted to move up and down. The type bars 19' that are mounted on the segment and their actuating devices may be of any suitable character, corresponding for example with the construction shown in Fig. 1. The means for shifting the segment 139 up and down comprise bars or links 140 pivotally connected at their upper ends to the segment and at their lower ends engaging plain studs or pins 141 that extend laterally outward from crank arms 142 fixed to a rock shaft 143 that has bearings in the sides of the base. Arms 144 rigid with the rock shaft and extending forward are provided with rollers 145 that underlie and are operative by shift key levers 146. The operation of either shift key lever rocks the shaft 143, thrusts up the links or bars 140 and shifts the segment 139 together with the type bars 140 thereon to upper case position. 100

The frame that supports the universal bar comprises a segmental body portion 147 having lateral extensions 148 provided with bearing pins 149 that bear in brackets 150 fixed to the stationary supports or posts 138. A guide rod 151 and two guiding pins 152 are rigid with the portion or frame 147 and extend rearward therefrom providing bearings for a universal bar frame 153 on which is mounted a curved universal bar proper 154 that is operative directly by the type bars. The universal bar frame is provided with a restoring spring 155 and is connected by a link 156 with an escapement dog carrier 110

150 155 160 165 170 175 180 185 190 195 200

85", conventionally shown. A center type guide 19^a of ordinary construction is fixed to the frame 147, 148 and shifts therewith. The type ends of the type bars coöperate with said guide. All forms of the invention may be provided with center type guides if found desirable.

The means for shifting the universal bar 154 and its supporting frame comprise upright arms 157 pivotally connected by shoulder screws 158 to the side portions of the frame 147. The lower ends of the arms 157 are formed with eyes which receive bearing blocks 159 that are held in place by caps 160. These bearing blocks are provided with downwardly extending lugs 161 having rounded heads and said bearing blocks are perforated to fit loosely over the studs 141 outside the links 140. The studs terminate just outside the bearing blocks when the latter are in normal position and stationary pins or rods 162 fixed to the sides of the base and projecting laterally inward therefrom in register with or in line with said studs terminate just short of the studs, leaving a slight space between them so as not to interfere with the up and down movement of said studs when the rock shaft 143 is rocked. These rods 162 are of the same diameter as the studs 141 and are adapted to receive and support the bearing blocks 159 when the latter are slid outward by means presently to be described for the purpose of disconnecting the universal bar from the case shifting mechanism. The ends of the studs 141 and of the rods 162 are preferably beveled or tapered slightly to facilitate the lateral disconnecting and re-connecting movements of the bearing blocks and the arms 157 which carry them. The disconnecting means comprise levers 163 and 164 pivoted at 165 on angular brackets 166 screwed or otherwise secured to the base frame 137 and extending inward therefrom. The pivots 165 are below the lugs 161. The right-hand lever 163 is a bell crank and has an upright arm 167 provided with a vertical opening or slot indicated at 168 which engages loosely with the rounded end of the associate lug 161. The other arm 169 of the bell crank extends horizontally outward and underlies a downward extension 170 on a special key lever 171 pivoted in the rear of the base and provided with a key which is disposed at the right-hand side of the key board. The left-hand lever 164 is substantially upright comprising an upper slotted arm 172 which loosely engages with the left-hand lug 161, said lever further comprising a downwardly extending arm 173. The lever arms 167 and 173 are operatively connected by a link or rod 174. The construction is such that when the special key lever 171 is operated the extension 170 thereon acting against the arm 169 will rock the bell

crank 163 and through the rod 174 will also rock the lever 164. The upwardly extending arms of said levers will swing outward away from each other and will act to shift the bearing blocks 159 laterally outward on to the stationary pins 162, thus disconnecting the rods 157 from the studs 141 as indicated by the dotted lines in Fig. 14. Following such disconnection it will be understood that an operation of either of the shift key levers 146 will be effective to shift the type bar segment 139 but not the universal bar 154 or its carrier frame 147, these parts remaining down in lower case position.

In order to restore the parts to the first position means are provided comprising a sleeve 175 that is slidably mounted on the left-hand rod 162. Connected with the slide or sleeve is a push rod 176 that passes through a somewhat larger opening 177 in the left-hand side of the base 137 and is provided outside the base with a key or button 178. A coiled spring 179 anchored to said base tends constantly to draw the sleeve toward the left, its movement in this direction being limited by a stop 180 on the rod 176. This stop arrests the sleeve in such position that its right-hand end is close to the left-hand bearing block 159 when the bearing blocks have been slid on to the rods 162. Consequently by pushing in the key 178 at this time the sleeve will contact with the said left-hand bearing block and force it back on to its stud 141. This movement of the bearing block operates through its lug 161 on the train of devices comprising the lever 164, link 174 and lever 163 to restore the right-hand bearing 159 to engagement with its stud 141. On releasing the key 178 the spring 179 will restore the sleeve to its left-hand position. A stop device 166^a may be provided having stop portions above and below the lever arm 169 to limit its movements in both directions and thus limit also the movements of the devices with which it is connected and which it controls.

A modification of the construction of Figs. 14-16 is illustrated in Fig. 17 wherein the lever 171 is replaced by a lever 181 pivoted at the rear of the base and provided with the usual restoring spring and finger key. Said lever 181 is provided with a downward extension 182 which at its lower end is formed with a slot indicated at 183 in which is loosely engaged, the lever arm 169. When the key lever 181 is depressed the top of the slot 183 engages with the lever arm to rock it and swing the right-hand bearing block 159 on to the rod 162. At the same time through the link 174 the lever 164 is caused to swing the left-hand bearing block to its inoperative position on its rod 162. While the lever 181 is maintained depressed by one finger the operator may, with a finger of the same hand, depress the right-hand

shift key which is in juxtaposition to the key of the lever 181. This leaves the left-hand free to operate the printing keys. On releasing the key lever 181 its spring will 5 restore it to normal position and the bottom of the slot 183 engaging with the under side of the lever arm 169 will operate on the train of devices starting with said lever arm to restore the bearing blocks to their studs.

10 Preferably the key lever 181 is provided with a locking key of a suitable construction, such as that found on the left-hand shift key lever of the No. 10 Remington machine, by which said key lever may be locked 15 down to maintain the universal bar withdrawn from the control of the shift key mechanism as long as may be desired.

It will be observed that in the Fig. 8 construction relative displacement is afforded 20 between the links that extend to the shiftable frame that supports the universal bar and the lateral pins or studs on the key controlled rock shaft, this displacement being caused by a downward movement of the 25 links by means comprising the accent key lever. On the other hand, relative displacement between the corresponding parts in the Fig. 14 construction is afforded by a lateral movement of the ends of the links lengthwise of the pins or studs, this lateral movement being caused by means comprising a 30 special key lever.

It will further be noted that the center 35 guide illustrated in the Fig. 14 construction is supported independently of the case shifting element or type bar support; that said center guide is shiftable simultaneously with said element to change the case position; and that said center guide is also shiftable 40 independently of said element, said center guide and the support on which it is mounted which is also the support of the universal bar being shiftable from upper case back to lower case position while said element or 45 typebar support remains quiescent.

It will also be understood that as far as the generic features of my various improvements are concerned the universal bar construction, mounting, escapement mechanism, 50 type bar actions and the type bar shifting devices may each and all be specifically different in construction from the several specific constructions herein shown and described.

55 Features specific to the construction shown in Figs. 14 to 17, inclusive, are not claimed herein as they form in part the subject-matter of divisional application Sr. No. 81,646 filed March 2, 1916.

60 What I claim as new and desire to secure by Letters Patent, is:—

1. In a typewriting machine, the combination with a shifting mechanism, of a type bar support connected to said shifting mechanism, and an independent universal

bar support also connected to said shifting mechanism but independently of said type bar support.

2. In a typewriting machine, the combination with case shifting mechanism comprising a key controlled shiftable element, of a universal bar mounted independently of said element, and means for automatically shifting said universal bar when said element is shifted. 75

3. In a typewriting machine, the combination with case shifting mechanism comprising a key controlled shiftable element, of a universal bar mounted independently of said element, and connections whereby 80 said universal bar shifts with said element.

4. In a typewriting machine, the combination with case shifting mechanism, of a universal bar supported from the frame of the machine, and means for shifting said 85 universal bar to change its normal position.

5. In a typewriting machine, the combination with case shifting mechanism comprising a key controlled shiftable element, of a universal bar supported from the frame 90 of the machine, and means for automatically shifting said universal bar when said element is shifted.

6. In a typewriting machine, the combination with case shifting mechanism comprising a key controlled shiftable element, of a universal bar supported from the frame of the machine, a shift key, and connections from said shift key both to said universal bar and also to said element. 95

7. In a typewriting machine, the combination of a platen, type bars, case shifting mechanism including a shift key for effecting a relative shifting movement between said platen and said type bars, and a universal bar mounted on the frame of the machine and operative directly by said type bars, said universal bar being shiftable by 105 said shift key.

8. In a typewriting machine, the combination of a platen, type bars, case shifting mechanism including a shift key for effecting a relative shifting movement between said platen and said type bars, a universal bar mounted on the frame of the machine 110 and operative directly by said type bars, said universal bar being shiftable by said shift key, and escapement devices operative by said universal bar.

9. In a typewriting machine, the combination of a platen, type bars, a type bar support, case shifting mechanism including a shift key for effecting a relative shifting movement between said platen and said type bar support, a universal bar mounted independently of said platen and also of said type bar support, said universal bar being operative directly by said type bars, and connections between said universal bar and said shift key. 120

10. In a typewriting machine, the combination of a platen, a type bar support, means for shifting said type bar support to change case, said means including a shift key, a universal bar mounted independently of said type bar support, and operative connections between said universal bar and said shift key.
11. In a typewriting machine, the combination of a platen, type bars, a type bar support, means including a shift key for shifting said support to change case, a universal bar mounted independently of said support and operative directly by said type bars, and connections between said universal bar and said shift key.
12. In a typewriting machine, the combination of a carriage, a platen thereon, type bars, a type bar support, means including a shift key for shifting said support to change case, a universal bar mounted independently of said support and operative directly by said type bars, carriage feeding devices operative by said universal bar, and operative connections between said universal bar and said shift key.
13. In a typewriting machine, the combination of a shiftable type bar support, type bars thereon, guiding devices for guiding said support during the shifting movements, a shiftable universal bar, and separate guiding devices for guiding said universal bar during shifting movements.
14. In a typewriting machine, the combination of a shiftable type bar support, type bars thereon, guiding devices for guiding said support during the shifting movements, a shiftable universal bar, said universal bar being operative directly by said type bars, devices for guiding said universal bar during its shifting movements, said devices being separate from the first recited guiding devices and parallel thereto, and a single key effective to shift both said support and said universal bar.
15. In a typewriting machine, the combination, of a shiftable type bar support, type bars thereon, guiding devices for guiding said support during the shifting movements, a shiftable universal bar, and guiding devices for guiding said universal bar during shifting movements, said last recited guiding devices comprising stationary perforated bearings, and shiftable pins co-operating with said perforated bearings.
16. In a typewriting machine, the combination of a shiftable type bar support, devices for guiding said support during its shifting movements, a shiftable frame, stationary bearings with which said frame slidably engages, a universal bar, and bearings on said frame with which said universal bar slidably engages.
17. In a typewriting machine, the combination of a shiftable type bar support, guid-
- ing devices therefor, a shiftable universal bar, and guiding devices for guiding said universal bar during shifting movements, said last named guiding devices being separate from said first recited guiding devices and comprising sets of perforated bearing elements and co-operating pin elements, one of said sets of elements being on a stationary part and the other of said sets of elements shifting with said universal bar.
18. In a typewriting machine, the combination of a shiftable type bar support, devices for guiding said support during its shifting movements, a shiftable frame, stationary bearings with which said frame slidably engages, a curved universal bar slidably supported on said shiftable frame, and type bars mounted on said type bar support and operative directly on said curved universal bar.
19. In a typewriting machine, the combination of a shiftable type bar support, a shiftable frame mounted independently of said type bar support, a universal bar mounted on said frame and movable relatively thereto, a key controlled rock shaft, a link connecting said support with said rock shaft, and a second link connecting said frame with said rock shaft.
20. In a typewriting machine, the combination of a shiftable type bar support, a shiftable frame mounted independently of said type bar support, a universal bar mounted on said frame and movable relatively thereto, a key operated rock shaft, crank arms on said rock shaft near its ends, a pair of links connecting said support with said crank arms, and a second pair of links connecting said frame with said crank arms.
21. In a typewriting machine, the combination with a shifting mechanism, of a set of type bars connected to be shifted thereby, and a universal bar independently connected to said shifting mechanism to be simultaneously shifted thereby.
22. In a typewriting machine, the combination with a shifting mechanism, of a type bar support and a universal bar support, and independent connections between said supports to said shifting mechanism.
23. In a typewriting machine, the combination with a shifting mechanism, of a type bar support, a universal bar support arranged over the type bar support, so as to be actuated directly by the type bars, and connections from both said supports to said shifting mechanism whereby they may both be shifted simultaneously.
24. In a typewriting machine, the combination with a shifting mechanism, of a type bar support mounted in the frame work, a universal bar also mounted in the frame work, and connections from both said supports to the shifting mechanism.
25. In a typewriting machine, the combi-

nation with a type bar support mounted in the frame work, of a universal bar support independently mounted in the frame work, and means for shifting both said supports,

5 26. In a typewriting machine, the combination of a type bar support, guide posts or brackets therefor, a universal bar support independently supported by said guide posts or brackets, and means for simultaneously 10 shifting both said supports.

27. In a typewriting machine, the combination with a type bar support and an independent universal bar support, of posts or brackets, means on said posts or brackets for 15 guiding both said supports, and means for shifting both said supports.

28. In a typewriting machine, the combination with a shifting mechanism, of a type bar support, an independent universal bar 20 support, and a series of links or arms independently connecting both said supports with said shifting mechanism.

29. In a typewriting machine, the combination with a type bar support, of a shifting 25 mechanism connected thereto; a universal bar support, and direct connections between the universal bar support and said shifting mechanism.

30. In a typewriting machine, the combination of a type bar support, a shift key operatively connected to said type bar support, a universal bar support, and independent 35 connections therefor to said shift key.

31. In a typewriting machine, the combination of a shiftable type bar support, a shiftable universal bar, a key controlled rock shaft, a crank arm on said rock shaft having a lateral stud or pin, a link connecting said support with said crank arm, a second link 40 connecting said universal bar with said stud, and means for affording relative displacement between said second link and said stud, said means comprising a printing key lever.

32. In a typewriting machine, the combination of a case shifting element, a shiftable universal bar, means controlled by a single key for simultaneously shifting said element and said universal bar, and means for shifting said universal bar independently of said 45 key.

33. In a typewriting machine, the combination of a case shifting element, a universal bar, means for simultaneously shifting said element and said universal bar, and means 55 for shifting said universal bar independently of said element.

34. In a typewriting machine, the combination of a case shifting element, a universal bar, means for simultaneously shifting said 60 element and said universal bar in one direction, and means for shifting said universal bar in the opposite direction independently of said element.

35. In a typewriting machine, the combi-

nation of a case shifting element, key actuated means for shifting said element, a universal bar, and means tending constantly to shift said universal bar, said key actuated means controlling said last recited means. 65

36. In a typewriting machine, the combination of a case shifting element, a shiftable universal bar, a key operative to shift said element and said universal bar simultaneously, and a second key operative to shift only said universal bar to vary its case position. 70 75

37. In a typewriting machine, the combination of a case shifting element, a shiftable universal bar, and two keys operative to shift said universal bar oppositely to vary 80 its case position, one of said keys operating also to shift said element.

38. In a typewriting machine, the combination of a case shifting element, key actuated means for shifting said element from 85 lower to upper case, a universal bar, spring means tending constantly to shift said universal bar from lower to upper case, and stops normally preventing the operation of said spring means. 90

39. In a typewriting machine, the combination of a case shifting element, key actuated means for shifting said element from lower to upper case, a universal bar, spring means tending constantly to shift said universal bar from lower to upper case, and stops normally preventing the operation of 95 said spring means, said stops being controlled by said key actuated means.

40. In a typewriting machine, the combination of a case shifting element, a shift key, a universal bar, spring means tending constantly to shift said universal bar from lower to upper case, and stop means normally preventing said spring means from 100 acting, said stop means moving automatically when said shift key is actuated to permit the spring means to become effective. 105

41. In a typewriting machine, the combination of a case shifting element, key actuated means connected with said element, stops controlled by said key actuated means, a universal bar, arms for shifting said universal bar to change its case position, springs holding said arms against said stops, and key controlled means for moving said arms away from said stops after the case shifting operation. 110 115

42. In a typewriting machine, the combination of a case shifting element, key actuated means connected with said element and comprising crank arms provided with lateral studs, a universal bar, devices comprising slotted arms for shifting said universal bar, the slots being engaged by said studs, springs holding the bottoms of said slots against said studs, and key controlled means for moving said arms away from said studs 120 125

when the machine is arranged for writing upper case characters.

43. In a typewriting machine, the combination of a case shifting element, type bars mounted thereon, key actuated means connected with said element and comprising crank arms provided with lateral studs, a universal bar, devices comprising slotted arms for shifting said universal bar, the slots being engaged by said studs, springs for holding the bottoms of said slots against said studs, and a printing key lever connected to one of said type bars and operative to move said arms to carry the bottoms of the slots away from said studs when the machine is arranged for writing upper case characters.

44. In a typewriting machine, the combination of a case shifting element, type bars mounted thereon, key actuated means connected with said element and comprising crank arms provided with lateral studs, a universal bar, devices comprising slotted arms for shifting said universal bar, the slots being engaged by said studs, a cross rod connecting said arms, springs for holding the bottoms of said slots against said studs, and a printing key lever connected with one of said type bars and provided with a device operative on said cross rod to overcome said springs after the case shifting operation.

45. In a typewriting machine, the combination of a case shifting element, key actuated means for shifting the same comprising crank arms having lateral studs, a shiftable frame mounted independently of said element, a universal bar movably supported by said frame, a pair of upright arms connected to said frame at their upper ends and provided at their lower ends with slots which are engaged by said studs, a cross rod connecting said arms near their lower ends, springs constantly tending to draw said arms upward, and a printing key lever provided with a downward extension that is operative on said cross rod when said frame is in upper case position.

46. In a typewriting machine, the combination of a case shifting element, a shiftable universal bar, means controlled by a single key for simultaneously shifting said element and said universal bar, a type bar provided with two types, and means for actuating said type bar comprising a key lever, said key lever when operating to print with one of its types acting automatically to shift said universal bar independently of said single key.

47. In a typewriting machine, the combination of a case shifting element, a shiftable universal bar, means controlled by a single key for simultaneously shifting said element and said universal bar, a type bar provided with two types, and means for

actuating said type bar comprising a key lever, said key lever when operating to print with one of its types acting automatically to shift said universal bar independently of said single key, said key lever when operating to cause the other of the types to print being ineffective to shift said universal bar.

48. In a typewriting machine, the combination of a case shifting element, a universal bar, a type bar operative on said universal bar, type bar operating means, and means for simultaneously shifting said element and said universal bar, said type bar operating means also being effective to shift said universal bar.

49. In a typewriting machine, the combination of a case shifting element, a universal bar, a type bar operative thereagainst, type bar operating means, and means for shifting said element and said universal bar in one direction, said type bar operating means being effective to shift said universal bar in the opposite direction.

50. In a typewriting machine, the combination of a case shifting element, a universal bar, a type bar operative thereagainst, type bar operating means, and means for shifting said element and said universal bar in one direction, said type bar operating means being effective to shift said universal bar in the opposite direction and independently of said element.

51. In a typewriting machine, the combination of a type bar support, type bars thereon, key operated means for actuating said type bars, a universal bar, and means for simultaneously shifting said type bar support and said universal bar from lower to upper case, certain of said type bar actuating means being effective to shift said universal bar automatically from upper case to lower case.

52. In a typewriting machine, the combination of a type bar support, type bars thereon, key operated means for actuating said type bars, a universal bar, and means for simultaneously shifting said type bar support and said universal bar from lower to upper case, certain of said type bar actuating means being effective to shift said universal bar automatically from upper case to lower case independently of said type bar support.

53. In a typewriting machine, the combination of case shifting mechanism including a shift key, a type bar, type bar operating means including a printing key, and a universal bar, said shift key being effective to shift said universal bar to change its case position and said printing key being also effective to shift said universal bar to change its case position.

54. In a typewriting machine, the com-

- bination of a shiftable type bar support, type bars mounted thereon including an accent type bar, actuating devices for said type bars, a type bar operated universal bar 5 shiftable with said type bar support, and means operative when the type bars are in upper case position to shift the universal bar back to lower case position in order to render the accent type bar when actuated ineffective on said universal bar.
55. In a typewriting machine, the combination of case shifting mechanism including a shift key, a type bar, type bar operating means including a printing key, and a universal bar, said shift key being effective to shift said universal bar to change its case position and said printing key being also effective to shift said universal bar to change its case position, said type bar being shaped to actuate said universal bar in one of its case positions but being ineffective at certain times when the universal bar is in its upper case position.
56. In a typewriting machine, the combination of case shifting mechanism including a shift key, a type bar operating universal bar, a type bar, and a printing key connected to said type bar, said printing key being effective at one time to cause said type bar to print and to actuate said universal bar and said printing key being effective at another time to cause said type bar to print and also operating automatically to shift said universal bar to change its case position.
57. In a typewriting machine, the combination of case shifting mechanism including a shift key, a type bar operating universal bar, a type bar, and a printing key connected to said type bar, said printing key being effective at one time to cause said type bar to print and to actuate said universal bar and said printing key being effective at another time to cause said type bar to print and also operating automatically to shift said universal bar to change its case position so that the type bar will be ineffective to actuate said universal bar.
58. In a typewriting machine, the combination of a key controlled case shifting element, a universal bar, a type bar having a face that is operative on the universal bar and having also a notch which renders said type bar ineffective on said universal bar, a printing key connected to said type bar, and means controlled by said printing key for effecting a relative shift between said universal bar and said type bar to bring said notch opposite said universal bar.
59. In a typewriting machine, the combination of a key controlled case shifting element, a universal bar, a type bar, a printing key connected to said type bar, said type bar being normally effective to actuate said universal bar, and means controlled by said printing key for effecting a relative shift between said universal bar and said type bar to render said type bar ineffective on said universal bar.
60. In a typewriting machine, the combination of a type bar support, means for shifting the same, a universal bar support shiftable with the type bar support and also shiftable independently thereof.
61. In a typewriting machine, the combination of a type bar support, a universal bar support, shift mechanism connected to both said supports so as to operate them in unison, and means for shifting the universal bar support independently of the type bar support.
62. In a typewriting machine, the combination of a type bar support, an independently mounted universal bar support, shifting mechanism, independent connections therefrom to both said supports whereby both said supports may be shifted together, and means whereby the universal bar support may be shifted relatively to the type bar support.
63. In a typewriting machine, the combination of a type bar support carrying a set of types including a notched type bar, a universal bar support arranged thereover and provided with a universal bar adapted to be actuated by the type bars, shifting mechanism for moving said supports concurrently, and means for shifting the universal bar support toward the type bar support so that when the notched type bar is actuated it will fail to act on said universal bar.
64. In a typewriting machine, the combination of a shiftable type bar support, a universal bar mounted to shift concurrently therewith, and means adapted to shift the universal bar back to normal position while the type bar support remains in shifted position.
65. In a typewriting machine, the combination of a shiftable type bar support carrying a set of type bars including a notched bar, a universal bar shiftable concurrently with said type bar support from lower case to upper case position, and means for shifting the universal bar back from shifted substantially to normal position while the type bar support remains in upper case position whereby the notched type bar is adapted to actuate the universal bar while the type bar support is in its lower case position but may be prevented from actuating the universal bar when the type bar support is in its upper case position.
66. In a typewriting machine, the combination of a shiftable type bar support and an independently mounted universal

bar support shiftable concurrently with the type bar support and also independently thereof.

67. In a typewriting machine, the combination of a shiftable type bar support, a shiftable universal bar support, all the type bars being adapted to actuate the universal bar while the type bars are in their normal lower case positions, means for shifting the universal bar back substantially to normal position while the type bars remain in upper case position, whereby one or more

specially constructed type bars of said set may be prevented from actuating said universal bar while the set of type bars are in 15 shifted or upper case position.

Signed at the borough of Manhattan, city of New York, in the county of New York and State of New York, this 29th day of October, A. D. 1915.

JACOB FELBEL.
